U.S. Appl. No. 29/372,108, Applicant: Ju-Won Cho, filed Oct. 15, 2010 entitled Blu-Ray Disk Player.

(Continued)

Primary Examiner — Nanda Bondade(74) *Attorney, Agent, or Firm* — Flynn, Thiel, Boutell & Tanis, P.C.**CLAIM**

The ornamental design for a blu-ray disk player with A/V receiver, as shown and described.

DESCRIPTION

FIG. 1 is a top front perspective view of a blu-ray disk player with A/V receiver showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
